UNITED STATES PATENT OFFICE.

JOHN C. BLEVNEY, OF NEWARK, NEW JERSEY.

AMALGAMATOR.

SPECIFICATION forming part of Letters Patent No. 310,172, dated January 6, 1885.

Application filed January 26, 1884. (No model.)

To all whom it may concern:

Be it known that I, JOHN C. BLEVNEY, a citizen of the United States, and a resident of the city of Newark, in the county of Essex and 5 State of New Jersey, have invented certain new and useful Improvements in Amalgamators, of which the following is a specification.

This invention relates to machinery for amalgamating metals—as gold, &c.—with quicksilver and similar substances; and the objects 10 of this invention are to provide an amalgamator with a large amalgamating-surface, and means for keeping the quicksilver in constant motion by paddles that have their bearing and 15 support out of the reach of the amalgamating materials. I attain these objects by the mechanism illustrated in the accompanying drawings, in which—

Figure 1 is an end view of a section of the 20 apparatus; and Fig. 2 a cross-sectional view of two jointed sections with attachments, through the line *a b* of Fig. 1.

Similar letters refer to similar parts throughout the several views.

25 The bracket A, attached to the side B of the channel B', forms the bearings C C' of the shaft S, to which is secured the double pulley P and the paddle-wheel F. The channel B' has its inner surfaces plated first with a coating 30 of copper and then with a coating of silver, preferably by the electro-plate process. Its side C forms an angle of about sixty degrees to the bottom O, which has a depression and pocket, *p*, provided with pipe H, and 35 through which the steam-pipe E passes. The paddle-wheel F is also coated in the same manner and with the same material as the inner surfaces of B', and is of such construction that when revolving it will fit and move close to 40 the sides of the channel B', but will not touch them. The reservoir I is connected by the pipe H to the pocket *p*, and has an overflow, *q*, on a level with the upper surface of O, forming the bottom of B'. 45

Operating the amalgamator, I prefer to have a series of sections secured water-tight together, forming a continuous channel, with a series of paddle-wheels, having one end of the channel closed by a head, D, and the other 50 open, to have the pipe H connect all the pockets and the receiving-tank I, and to have the pipe E, supplied with steam, pass through all the sections. The quicksilver supplied to the

apparatus will fill the pipe and pockets until overflowing at *q*, and any ore amalgamating 55 with it will increase its bulk. Unless drawn off by K or similar means, the quicksilver will be kept at a level to the overflow during the running of the apparatus and be always within reach of the paddles. Revolving the 60 paddles by means of the pulleys or similar contrivances and admitting the pulverized ore and water, the quicksilver will be mixed with them and amalgamate with the metal contained therein, the whole being propelled by the paddles to the next pocket, where the amalgam 65 will sink and flow through the pipe H into the tank I. The same is repeated until the series is passed, when the water and powder, free from metal, flows out the open end of the channel B'. By mixing the quicksilver with the 70 pulverized ore and water the largest possible surface for amalgamating is obtained. The shaft S, having the bearings and supports in the frame A outside of the channel B, enables 75 me to keep the oil and lubricants from mixing with ore, and so prevent amalgamation, while the inclination of the shaft enables me to have the paddles almost wholly in the channel B', enabling the sides of the same to 80 form an absolute guide for the material. The heating powers of the steam applied helps the amalgamation.

I am aware that prior to my invention amalgamators have been constructed with paddles, 85 and I therefore do not claim them broadly. In one case known to me an inclined shaft has its bearings outside of the amalgamating-vessel, but in such instance there is no paddle-wheel or stirring device fitting the vessel, but 90 an annular shield is made to fit over the rim of a wheel rigidly secured to the shaft.

I am also aware that shafts of stirring devices have been arranged at an inclination, but in all amalgamators of this class heretofore made the inclined shaft has a bearing in the amalgamating-vessel. This construction I avoid, and I would add, in relation to the connections of the pockets with the reservoir, that the arrangement is substantially as shown, 100 to maintain a constant level of mercury or amalgam by allowing reflux and overflow, as described.

I claim as new and desire to procure by Letters Patent—

1. In an amalgamator, the combination,

with a sectional channel, B', provided with pockets, of a paddle-wheel revolving in line with and fitting close to said channel, and secured to a shaft mounted outside of and at an 5 inclination to the level of said channel, for the purpose substantially as set forth.

2. In an amalgamator, a series of paddle-wheels, each secured to a separate shaft revolving at an inclination to the level of the 10 apparatus and parallel to one another, said shafts being journaled outside of the amalgamating channel, in combination with a straight channel formed of a series of sections secured together, each having a pocket communicating with a pipe connecting them and 15 to a reservoir, for the purpose substantially as set forth.

3. In an amalgamator of the kind described, a series of pockets for holding amalgam, each 20 pocket connected by a pipe to one adjacent and to a reservoir, for the purpose substantially as described.

4. The combination, in an amalgamator, of a series of sections having each a pocket communicating with one another and a reservoir, 25 and a steam-pipe passing through them, for the purpose substantially as set forth.

5. In an amalgamator, the combination of a series of sections forming a channel having the pockets p, the connecting-pipe H, the 30 steam-pipe E, the reservoir I, and a series of paddle-wheels mounted at an angle to the level of the apparatus, and means for revolving them, all for the purpose substantially as set forth.

In testimony that I claim the foregoing as my invention I have signed my name, in presence of two witnesses, this 24th day of January, 1884.

JOHN C. BLEVNEY.
